UNITED STATES PATENT OFFICE.

GEORGE R. KELSEY, OF WEST HAVEN, CONNECTICUT.

MANUFACTURE OF BUCKLES.

SPECIFICATION forming part of Letters Patent No. 316,790, dated April 28, 1885.

Application filed January 2, 1885. (No model.)

To all whom it may concern:

Be it known that I, GEORGE R. KELSEY, of West Haven, in the county of New Haven and State of Connecticut, have invented new Improvements in the Manufacture of Buckles; and I do hereby declare the following, when taken in connection with accompanying drawings and the letters of reference marked thereon, to be a full, clear, and exact description of the same, and which said drawings constitute part of this specification, and represent, in—

Figure 1, a perspective view of the buckle complete; Fig. 2, the frame as formed preparatory to bending the ends; Fig. 3, a side view of the same, showing the commencement of the bend in broken lines; Fig. 4, a side view of the bend as made to receive the tongue-bar; Fig. 5, the bend completely formed around the tongue-bar; Fig. 6, a side view of the frame, showing the usual method of manufacture; Fig. 7, the same illustrating the usual method of bending; Fig. 8, a longitudinal section through the dies which form the ends.

This invention relates to an improvement in the manufacture of that class of buckles which are made from wire; and it consists of a frame and tongues, the tongues being formed on the end of the wire which makes the loop, the bend being of such a nature as to turn the tongues at right angles to the loop, and inside the ends of the loop the two ends of the wire frame bent around the loop close to the tongues, and such as used for suspender and garment buckles, and commonly known as the "Hartshorn buckle."

In the usual method of making this class of buckles the frame is bent into shape, leaving the two ends extending therefrom, as seen in Fig. 2, broken lines indicating the extending ends. These ends require to be reduced in thickness in order to make the bend to form the hinge, and this has been done by striking the ends between flat surfaces, reducing the thickness from each side, as seen in Fig. 6, leaving a thin flat projecting tongue, *a*. This striking of the two ends and flattening it from both sides so hardens the metal that it is necessary to anneal it before the bend can be made in the end portion to encircle the tongue portion, as seen in Fig. 1. Then in many cases the surface of the metal will be broken at the shoulders or points where the flattening commences, and very many frames are lost because

of the separation of the flattened portion in the bending operation. Again, the annealing operation so softens the entire frame that it is very much weaker than it would be were it not for such annealing, consequently very much larger wire must be employed to produce a buckle of the same strength than would be necessary were it not for this annealing operation. In making the bend in the usual construction the flat portion is struck to turn the extreme end up at right angles to the plane of the frame and carry the bent or U-shaped part backward, as seen in Fig. 7. Then the tongue portion is laid into the bend, and the ends of the frame turned down over the tongue portion. In this method of bending, the bend commences near the shoulders or weakest part of the frame, and many frames are broken because of this method of bending.

The object of my invention is to avoid the annealing and the frequent breaks referred to; and it consists in striking the ends from one side only, leaving the other side in its rounded shape, and so as to preserve the natural surface on that side, and then making the bend from the extreme end toward the frame, as more fully hereinafter described. The frame is cut from wire of the required length bent to shape, as seen in Fig. 2, broken lines indicating the ends of the frame. The ends are reduced in dies such as seen in Fig. 8, A representing one die, in which cavities *b* are made, corresponding in relative position to the two ends of the frame, these cavities being concave in transverse section, the other die, B, presenting a corresponding flatsurface. The ends of the frame laid in the cavities *b*, the flat-faced die brought forcibly thereon will flatten the end of the frame upon one side only, leaving the other convex in transverse section, as seen in Fig. 3, and in section representing the ends in Fig. 2. This leaves the rear or rounded side of the frame without any material displacement of the metal. Thus flattened, the ends are bent into shape, beginning from the extreme end, as indicated in broken lines, Fig. 3, the end carried over toward the frame, as seen in Fig. 4. Then the tongue is laid into the bent end of the frame, and the ends of the frame closed over the bar *d* of the tongue, as seen in Fig. 5. In this construction the hinge or knuckle of the frame presents a nicely-

rounded surface, and because the texture of the metal on one side is not materially disturbed, and because the bend is made from the extreme end toward the frame, no such distress of metal occurs as when the frame is flattened and bent from the frame outward, as in the old method of manufacture, and because of this method of striking and bending the ends, avoiding such distress of the metal, the annealing heretofore necessary is avoided, and I am enabled to produce buckle-frames of the same strength of much lighter material than can be done under the old method of manufacture.

I claim—

The herein-described improvement in the manufacture of wire buckles, consisting in striking the ends of the frame flat upon one side, leaving the other rounded or convex in transverse section, then bending the ends from their extreme end toward the frame around the tongue to form the hinge, substantially as described.

GEO. R. KELSEY.
